(57) **CLAIM**

The ornamental design for a LED grow light, as shown and described.

DESCRIPTION

FIG. 1 is a front elevational view of a LED grow light showing my new design;

FIG. 2 is a rear elevational view thereof;

FIG. 3 is a top plan view thereof;

FIG. 4 is a bottom plan view thereof;

FIG. 5 is a left side view thereof;

FIG. 6 is a right side view thereof;

FIG. 7 is a perspective view thereof; and,

FIG. 8 is another perspective view thereof.

The broken lines shown illustrate portions of the LED grow light that do not form part of the claimed design.
